IMPACT BIT

Application filed September 11, 1928. Serial No. 305,190.

This invention relates to a drilling tool of the percussion type for earth boring, wherein the percussive action is obtained by rotation of a drive stem in relation to the 5 drill string.

In the rotary drilling of well holes of great depth, the hole drilled is seldom straight, due primarily to the slanting formation and the encountering of boulders of various shapes in the formation which cause the 10 drilling tool to be deflected laterally. In percussion or standard drilling, the hammering acting in a vertical direction contributes to a relatively straight advance of the tool. The 15 present invention contemplates a tool operable as to cutting action by percussion and as to operation from the surface by rotation of the drive stem.

It is a primary object of this invention to 20 provide a tool which has a bit reciprocable by rotation of the drive stem and rotatable from the drill string so as to progressively change the location of the impact of the cutting blades. Other objects of this invention 25 are to provide details of structure whereby a durable, strong, simple, and efficient drill of the character described is obtained, one which is economical to manufacture and easy to manipulate and operate.

These objects together with other objects 30 and corresponding accomplishments are obtained by means of the embodiment of my invention illustrated in the accompanying drawings, in which:—

Fig. 1 is a vertical section through a well 35 hole showing a core drill in section and partly in elevation; Fig. 2 is an elevational view partly in section on an enlarged scale showing the cam coupling between the drive stem and the tool stem; and Fig. 3 is a section as seen on the line 3—3 of Fig. 1.

Referring with more particularity to the 40 drawings, a well hole 5 is shown and disposed therein in cutting position is the bit. Extending from the surface is a string of 45 drill pipe, a fragment of which is indicated by 6. Attached to the drill pipe in any suitable manner is an adapter 7 having a threaded socket to receive the threaded end of a 50 shell 8. The cage formed by the adapter and

shell houses a mechanism for changing rotary into reciprocating motion. A closure plate 9 for the shell is provided at the lower end and has an opening at the center thereof for the passage of the tool stem. Adjacent 55 its upper end is a guide 10 for the drive stem. Intermediate the guide and the closure plate is a thrust bearing plate 11.

Extending through the closure plate so as to be reciprocable therein is a hollow tool 60 stem 12 forming a core retainer and having attached thereto at the lower end a percussion core bit 13. This bit may be of any suitable type, and is herein shown as having four blades there being a core mouth not shown. 65 The upper portion of the tool stem is externally square and extends through a corresponding square opening in the thrust bearing plate 11, so as to be held against rotation in relation to the shell and to permit reciproca- 70 tion. Clamped to the tool stem is a collar 14 serving as a seat for a compression spring 15, the latter being interposed between the bearing and the seat. Below the seat and resting upon the closure plate is a buffer 75 spring 16. The compression spring tends to advance or project the tool stem and produces the impact or cutting stroke of the bit. The buffer spring is to prevent shock in the cam as will be later described. Se- 80 cured to the upper end of the tool stem is a cam follower 17 in the form of a collar, there being projections on its lower face extending axially of the tool stem. These projections have an inclined approach face 18 and a 85 drop-off face 19.

Extending through the drill pipe is a hollow drive stem, a fragment of which is indicated by 20 in Fig. 1. It carries at its lower end a cam sleeve 21. Secured to the cam 90 sleeve is a cam plate 22 forming in effect a collar about the tool stem. The cam 22 has projections 23 extending longitudinally of the stems for coaction with the projections on the follower. Interposed between the bearing 95 11 and the cam 22 is a bearing washer 24. A core barrel liner 25 secured in the tool stem 12 is slidably received in drive stem 20 so as to provide a slip joint connected and to protect the core captured.

The compression spring maintains the follower in engagement with the cam. When the follower has its high dwells resting upon the projections 23, as shown in Fig. 2, the 6 tool stem and its bit will be retracted. The compression spring at this time will have energy stored therein for advancing or projecting the bit upon its impact stroke. As the 10 cam and follower rotate with respect to one another, the tool stem is retracted, the inclined faces 18 riding over the projections 23 until the bit is fully retracted. Further movement then causes the cam follower to drop off the projections 23, the compression 15 spring expending its stored energy to cause a blow. In the operation of the device, the drive stem 20 may be rotated, and the drill pipe maintained relatively stationary, being preferably turned slowly so as to position the 20 blades of the bit at different angular positions at each blow. Obviously, the drive stem may be maintained stationary and the drill pipe rotated. However, upon relative rotation of the drive stem and drill pipe, the bit 25 is reciprocated to cause boring of the hole. It will be noted that there is suitable provision made for circulation.

What I claim is:—

1. A drill for well holes comprising a percussive core bit, a rotatable operating head 30 including a tubular shell adapted to be connected to a drill pipe, a hollow tool stem on said bit reciprocably mounted in said shell and held against rotation in relation thereto, 35 a cam member on said tool stem, a thrust bearing in said shell, a hollow drive stem rotatably mounted in said shell having a slip joint connection with said tool stem, a cam sleeve on said drive stem having a cam plate 40 interposed between said bearing and said cam member, said cam member and cam plate having coacting projections extending axially of said stems with inclined approach faces and drop-off faces, and a spring tending to project said tool stem and bit on its cutting 45 stroke, said tool stem and drive stem forming a core barrel.

2. A drill for well holes comprising a percussive core bit, a rotatable operating head 50 including a tubular shell adapted to be connected to drill pipe, a hollow tool stem on said bit reciprocably mounted in said shell and held against rotation in relation thereto, a cam follower member on said tool stem having axially extending projections with inclined approach faces and drop-off faces, a thrust bearing in said shell, a hollow drive stem rotatably mounted in said shell and having a slip joint connection with said tool 55 stem, a cam sleeve on said drive stem nested over said cam follower member and provided with a cam plate interposed between said bearing and said follower member including projections extending axially of said stem 60 for coaction with the projections on said fol-

lower member and a compression spring disposed between said bearing and said tool stem tending to project said tool stem and bit on the cutting stroke, said tool stem and drive stem forming a core barrel.

In witness that I claim the foregoing I have hereunto subscribed my name this 6th day of August, 1928.
